UNITED STATES PATENT OFFICE

SARA ROSENFIELD, OF CHICAGO, ILLINOIS

OVERSHOE

Application filed February 7, 1928. Serial No. 252,485.

This invention aims to provide a protector for shoes and stockings, so constructed that it can be put on and taken off easily, the legging being reinforced so that it will stand erect, even though it is made of material which is somewhat flexible.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings:—

Figure 1 shows in perspective, a device constructed in accordance with the invention;

Figure 2 is a cross section on line 2—2, Figure 1.

The device forming the subject matter of this application may be made of any suitable material or combination of materials, and it includes a body, sometimes formed of rubber and shaped to conform to the outline of a shoe, whatever the outline of the shoe may be. In the rear end of the body 1, at the back thereof there is an opening 2. This opening 2 is adapted to receive the heel 3 of the article of footwear, and the size of the opening 2 will be regulated by the cross sectional shape of the heel 3. The heel may be of any size and shape, and the article can be used with a shoe which has no heel at all. A trough-shaped legging 4 is secured in the rear end of the body 1 and has straight and substantially vertical forward edges 5. The legging 4 is preferably made of cravenette or rubber, like the body 1, and reinforcing strips 6 are secured to the inner surfaces of the legging 4 along the vertical forward edges 5, the strips 6 being made of cravenette or rubber, canvas, or any suitable material. Stiffeners 7 are housed within the reinforcing strips 6 and are held by the reinforcing strips 6 against the

sides of the legging 4. The stiffeners 7 are resilient or springy, and may be made of metal, whalebone, celluloid or any other substance having the necessary flexibility and stiffness. The reinforcing strips exercise a double function. First, they house and retain the stiffeners 7 and, second, they reinforce the legging 4 because they are secured to the legging along the edges 5 on the legging. At its upper end, the legging 4 is extended to form a band, the separable ends 9 of which are united detachably by a fastener 10 of any desired sort. For the sake of adjustment, more than one of the fasteners 10 are used. The numeral 11 marks a band which is located below the band 8, the band 11 being made up of separable parts, as shown at 12, the overlapped ends of the parts 12 being held together by separable fasteners 14. The rear ends of the parts 12 of the band 11 extend between the legging 4 and the reinforcing strips 6, and, the band 11 is held assembled with the article. The function of the bands 11 and 8, of course, is to hold the legging 4 about the leg of the wearer.

The device is so constructed that it will afford adequate protection in rainy or sloppy weather not only for a shoe but, as well, for the stocking of the wearer, it being a matter of common knowledge that water very often is spattered up on the back of a stocking.

By way of summary, the device hereinafter claimed is an article which, although capable of standing erect, nevertheless possesses flexibility and to attain these ends, there is provided the body 1 having heel-receiving means 2, a trough-shaped legging 4 being mounted on the body. Means 11 is extended forwardly from the legging 4 and constitutes means for securing the legging on the leg of the wearer. The legging will stand erect, owing to the presence of the stiffeners 7, but the flexibility of the legging is enhanced by the fact that the space "A—B" between the lower edge 31 of said means 11 and the upper edge 30 of the body 1 is open, and of greater length than the distance "B—C" from the lower edge 31 of said means 11 to the top 32 of the legging. The flexibility of the legging is further enhanced by the fact that it has the

straight forward edges 5, and because the legging is shallower, as shown at "D—E" in Figure 2 than the heel receiving means 2, measured from the rear 33 of the over-shoe 5 toward the toe 34 thereof.

What is claimed is:—

An over-shoe comprising a body having a hole through which a heel can protrude, a trough-shaped legging mounted on the body, 10 means extended forwardly from the legging for securing the legging on the leg of the wearer, the flexibility of the legging being enhanced by the fact that the space between the lower edge of said means and the upper 15 edge of the body is open and of greater length than the distance from the lower edge of said means to the top of the legging, and the flexibility of the legging being further enhanced by the fact that it has straight forward edges and is shallower, throughout its 20 entire length, than the said hole, measured from the rear of the overshoe toward the toe thereof, and stiffeners extended longitudinally of the legging and constituting means 25 whereby the legging will stand erect and hold its place on the leg of the wearer when the securing means is detached from the leg of the wearer.

In testimony that I claim the foregoing as 20 my own, I have hereto affixed my signature.
